UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

MACHINE FOR ASSEMBLING AND DISTRIBUTING TYPE.

1,094,064.

Specification of Letters Patent.

Patented Apr. 21, 1914.

Application filed March 28, 1906. Serial No. 302,378.

To all whom it may concern:

Be it known that I, HARRY C. GAMMETER, a citizen of the United States, residing at Cleveland, in the county of Cuyahoga and State of Ohio, have invented a certain new and useful Improvement in Machines for Assembling and Distributing Type, of which the following is a full, clear, and exact description, reference being had to the accompanying drawings.

The object of this invention is to provide a simple and efficient hand-actuated machine for assembling and distributing type.

The machine is well adapted for use in conjunction with a hand printing machine. It carries a supply of type and has hand-operative mechanism which may assemble the type in desired words in a temporary holder. The holder may then be transferred to the printing mechanism, and, after the matter is printed, the type re-transferred to the holder, which is then placed in the present machine and the type distributed. The invention is particularly well adapted for embodiment in a small office machine using type adapted to print in imitation of type-written matter—the various characters of such type having all the same sized body.

The invention is hereinafter more fully described and its essential characteristics set out in the claims.

The drawings fully disclose my invention.

Figure 1 is a central vertical section thereof. Fig. 2 is a front elevation. Fig. 3 is a plan. Fig. 4 is a partial horizontal section on the line A—A of Fig. 1 looking down. Fig. 5 is a similar view on a line B—B of Fig. 1 looking upward. Fig. 6 is an enlarged, partial bottom plan, sectioned on the line C—C of Fig. 1. Fig. 7 is a sectional side elevation of the distributing arm. Fig. 8 is a similar view of the assembling arm.

In the embodiment of the invention shown in the drawings, a stationary vertical drum 1 is provided, which is shown as carried by a wall, plate 2 which has projecting from it studs 3 connected to the drum. The drum is composed of spiders 4 on which are mounted longitudinal rails 5. The rails have overhanging edges, and thus provide undercut channels between them which are adapted to hold type having grooves in their edges, the

drum being thus a storage or supply member for the type. The types are preferably of the form shown at 35 in Fig. 6.

Mounted axially in the drum is a shaft 7 on which is a bevel gear 8. This gear is loose on the shaft, and carries one or more pins 9 which extend loosely through a collar 10 secured to the shaft. By this means the gear is compelled to rotate with the shaft while the shaft may slide some distance through the gear. This gear 8 meshes with another gear 11 which is on a horizontal shaft 12 extending to the front of the machine. On the front end of this machine is a knob 13 by which it may be turned, such action rotating the shaft 7. On the ends of the shaft 7 are a pair of arms 14 and 15, one above the drum and the other below it. Secured to the drum in a stationary manner is a dial 16 surrounding the shaft 12. On this shaft is a pointer 17 so adjusted that it points to the character on the dial corresponding to the drum channel with which the ends of the arms 14 and 15 are alining—it being understood that each channel carries type of one character. The arms 14 and 15 are adapted to carry temporary holders 18 and 19 respectively, each of which is arranged to carry the type in a single column with its face visible. By turning the knob 13 these holders are thus brought over or under the channels which contain the type corresponding to the character on the dial opposite the pointer. The shaft 7 has a limited up and down movement, and mechanism is provided, to be hereinafter described, which operates to distribute type from the tube 18 into the channel beneath the same when the shaft is lowered and to assemble type from the drum into the holder 19 beneath it when the shaft is elevated. This shaft 7 is mounted to have the limited longitudinal movement referred to by reason of a pair of springs 21 and 22 surrounding the shaft and held between collars 23 and 24 rigid thereon and loose collars 25 and 26. Pins 32 carried by the shaft occupy slots in the collars 25 and 26, thus allowing some movement lengthwise of the shaft. These pins, however, prevent the collars from coming into frictionally gripping engagement with the bearings of the shaft in its normal

55

position. They do not, therefore, interfere with the free rotation of the shaft under the influence of the knob 13. Secured to the shaft is a grooved collar 28 in which extends a crank arm 29 carried by a rock shaft 30 on the forward end of which is a key lever 31. This key lever has two keys on opposite sides of its axis. When one of these keys is depressed the shaft is thereby drawn downward, while when the other is depressed it is raised.

In assembling the type from the drum into the temporary holders 19, the knob 13 is turned until the pointer indicates the character desired, when the lever key 31 is depressed to raise shaft 7. This raises the arm 15 and causes a dog 33 carried thereby to engage a star wheel 34 mounted on a wire 36 behind the corresponding type channel, there being a wheel for each channel. The teeth of this wheel on its forward side engages the type 35 and the movement of the wheel caused by the actuator or dog acting on it shoves downward and releases the bottommost type, which passes into tube 19. A suitable stop, as for example, a split ring 38, is provided on this tube to prevent the type from dropping out. Every time shaft 7 is raised a type is fed from the drum into the tube 19. Between the depressions of the finger key the arms are rotated to bring them in alinement with the channel desired. The operation is thus to alternately rotate the knob and depress the proper finger key, this operation resulting in assembling type into desired words in the tube 19. Suitable springs 40 and 41 act on the dog 33 and the star wheel 34. Spring 41 may conveniently be double, like a hair-pin, and act on two adjacent star wheels. To prevent improper positioning of the tube 19 in its socket of the arm 15, I form a notch 45 (Fig. 8) in the upper end of the tube and a small projection 46 which engages this notch when the tube is in place. To insure the tube being in alinement with the type channel, I provide a tapered pin 47 (Figs. 6 and 8), which, as the arm approaches the drum, engages in the channel adjacent to the one being operated upon and thereby accurately positions the arm.

The distributing arm 14 carried at the upper end of the shaft 7, has near its forward end a star wheel 50 adapted to engage the type in the tube 18, or just below it. This star wheel is operated by a pawl 51 which is loosely pivoted on the arm and is adapted to be raised by engagement with the uppermost spider whenever the shaft 7 is drawn downward. The pawl is so carried by the arm that it may have backward as well as upward movement, by reason of having slots and enlarged openings around the supporting points, as shown in Fig. 7.

Suitable springs 52 and 53 act on the pawl

to keep it in place and allow this movement and a detent spring 54 acts on the star wheel. A pin 55 is carried by this arm to engage in the channel adjoining to the one in action to cause accurate alinement. The operation of the arms 14 and 15 is therefore, similar. Arm 14 however, carries the distributing star wheel 50; as explained, while at the lower end of the drum the star wheels are carried by the drum itself, one for each type channel.

It will be seen from the above description that the machine is very simple in construction. It is also simple in operation, it being only necessary to rotate the knob with one hand and operate the key lever with the other to distribute or assemble as desired. The temporary type holders are removed from the machine when filled and their contents transferred to a printing mechanism, or a printing mechanism might be provided which would receive and clamp the holders with the type.

I claim:

1. The combination with assembling mechanism and distributing mechanism, of temporary type holders arranged to be removably carried by either of said mechanisms, said type holders comprising split tubes, the edges adjacent to the split being adapted to occupy grooves in the type.

2. The combination with a vertical supply member of hand actuated means for distributing type into the upper end of it, hand actuated means for assembling type from the lower end of it, and split tube type holders adapted to engage grooves in the type and arranged for coöperation with either of said means.

3. The combination of a type supply drum adapted to carry columns of type, holders for the type to be distributed or assembled, each adapted to carry a column of type, the holder and drum coöperating and one of them being movable about an axis coincident with the axis of the other, mechanism for distributing type, mechanism for assembling type, and hand actuated means for operating either mechanism.

4. The combination of an upright storage drum having on its periphery a plurality of parallel upright holders for individual type, a vertical shaft at the axis of said drum, hand operated mechanism for rotating said shaft, an interchangeable column type holder, supporting devices therefor adjacent to the lower end and upper end of the drum respectively, mechanism for feeding type to the column type holder from the drum and to the drum from the column typeholder when in another position, the typeholder and drum being adapted to have their mutual presentation changed laterally by reason of one of them being carried by said shaft.

5. The combination of a storage drum having about its periphery a plurality of column typeholders, an individual column typeholder from which type may be distributed into the drum, an individual column typeholder into which type may be received from the drum, mechanism interposed between the respective typeholders and the corresponding ends of the drum for controlling the assemblage and distribution, a shaft at the axis of the drum, and means whereby the rotation of the shaft changes the presentation of the drum and typeholders to each other. 10
15. 6. The combination of a stationary vertical multichanneled supply drum and a pair of typeholders, mechanism for distributing type from one holder into the drum, mechanism for assembling type from the drum into the other holder, means mounted on an axis coincident with the axis of the drum for supporting said typeholders, and hand-actuated means for operating the distributing mechanism and the assemblage mechanism. 20
25. 7. The combination of a stationary vertical multi-columned supply drum formed of rails adapted to hold grooved type, a type holder comprising a split tube formed to engage in the grooves of type, mechanism for assembling type from the drum into the holder, means mounted on an axis coincident with the axis of the drum for supporting said type holder and assembling mechanism, and hand actuated means for operating the assembling mechanism. 30
35. 8. The combination of a supply drum having typeholding rails with overhanging edges adapted to confine grooved type, a shaft journaled therein, an arm on said shaft, a type holder adapted to be removably carried by said arm and consisting of split tube, the edges of which occupy the grooves of the type, and means for releasing type from said holder. 40
45. 9. The combination of a supply member, a rotatable shaft, a type holder carried thereby, means for rotating the shaft to bring the type holder into alinement with the proper channel of the supply member, and means for moving the shaft longitudinally to transfer the type. 50
55. 10. The combination of a stationary supply drum, a rotatable shaft journaled therein, a removable type holder carried thereby, means for rotating the shaft to bring the type holder into alinement with the proper channel in the supply drum, and means for moving the shaft longitudinally to transfer the type. 60
65. 11. The combination of a type supply drum, a shaft journaled axially thereof, an arm on said shaft opposite the end of the drum, a type holder carried by said arm, mechanism for releasing type one at a time to or from said holder, and means for moving the shaft longitudinally to actuate said mechanism. 70
75. 12. The combination of a type supply drum, a shaft journaled axially thereof, arms on said shaft opposite the ends of the drum, said arms being adapted to carry type holders, mechanism on one arm for releasing type one at a time from its holder, mechanism on the drum for releasing type to the other holder, and means for actuating either of said mechanisms. 80
85. 13. The combination of a type drum, a shaft rotatably journaled therein and movable longitudinally, said shaft being adapted to carry type holders, means for rotating said shaft, means for moving said shaft in either direction, and means whereby movement in one direction releases type to pass into the drum, and movement in the other direction to pass out of the drum. 85
90. 14. The combination with type having beveled feet, of a supply member having a series of parallel type channels, a series of releasing devices for the type in the channels adapted to operate on their beveled feet, and traveling means adapted to operate any of said devices. 90
95. 15. The combination of a supply member having a series of longitudinal type channels, a series of star wheels in said channels by their movement adapted to release the type, and traveling mechanism for actuating said star wheels, and means for moving said mechanism from one star wheel to another. 100
100. 16. The combination with type having their feet beveled, of a supply member, a distributing member adapted to carry a type holder and having a star wheel adapted to engage the foot of the type in the holder, and means for operating said star wheel to release the type. 105
110. 17. The combination of an upright storage member, distributing mechanism located above said member, assembling mechanism at the lower end of said member, and hand-actuated means common to the two mechanisms and adapted to operate either mechanism. 110
115. 18. The combination of an upright storage member, type distributing mechanism above the same, type assemblage-actuating mechanism below the same, a rotatable shaft by which said mechanisms are carried, and means for rotating said shaft. 115
120. 19. The combination of an upright storage member having type channels, a type distributing holder above the same, a type assemblage holder below the same, a rotatable shaft by which said holders are carried, means for rotating said shaft, and an indicator for determining the position of the holders with reference to the type channels. 125
130. 20. The combination of an upright storage

member, distributor-actuating mechanism above the same, assemblage actuating mechanism below the same, a rotatable shaft by which said mechanisms are carried, means for rotating said shaft, and mechanism for moving said shaft axially in either direction to distribute or assemble.

21. The combination of a storage device, means for feeding type thereto, means for discharging type from another point thereof, a member movable in one direction to operate one of said means and movable in the other direction to operate the other of said means, mechanism for holding said member normally in an intermediate position, and mechanism for shifting said member in either direction.

22. The combination of a channeled storage member, means for feeding type thereto, means for discharging type therefrom, a shaft movable in one direction to operate one of said means and movable in the other to operate the other of said means, means for rotating said shaft to bring the distributing and assembling actuators opposite the desired channels, and mechanism for shifting said shaft in either direction.

23. The combination of a storage member, an actuator for distributing type into one end thereof, an actuator for assembling type from the other end thereof, means for concurrently moving said actuators to position them with reference to the storage member, and means for operating either actuator.

24. The combination of a supply member, mechanism for distributing type into one end thereof, mechanism for assembling type from the other end thereof, means for concurrently positioning said mechanisms, to position them with reference to the supply member, and means for concurrently moving the actuators of said mechanisms in one direction to operate one of them and in the other direction to operate the other of them.

25. The combination with a storage member, of a distributing mechanism, assembling mechanism and hand-operated means to move said mechanisms concurrently in one direction or the other, one of said movements operating the distributing mechanism and the other of said movements operating the assembling mechanism.

26. The combination of an upright supply drum, a vertical shaft journaled axially thereof, distributing mechanism carried by said shaft above the drum, and assemblage mechanism carried by said shaft below the drum, a horizontal shaft geared with the vertical shaft, a pointer and dial, one member of which is carried by said horizontal shaft, and means for operating the distributing and assembling mechanisms.

27. The combination of a storage device, a shiftable member, means for distributing type into the storage device operated by the

movement of said member in one direction, means for assembling type from another point of the storage device operated by movement of said member in another direction, and a pair of finger keys connected with said member, one adapted to move it in one direction and the other in the other.

28. The combination of an upright drum, a shaft journaled therein, means for distributing type into the drum operated by longitudinal movement of the shaft in one direction, means for assembling type from the drum operated by longitudinal movement of said shaft in the opposite direction, and a pair of finger keys connected with said shaft, one adapted to raise it and the other to lower it.

29. The combination of a supply member formed of parallel rails with overhanging edges adapted to provide between them channels for type grooved on its opposite sides, a temporary typeholding member in the form of a split tube, the edges of which may engage the grooves in the opposite sides of the type, a movable member adapted to removably carry the typeholder, means for moving said member crosswise of the supply member and for positioning it with the edges of the tube adjacent to the split alining with the overhanging edges of rails, and means for releasing type in one of said members and allowing it to pass into the other.

30. The combination of a stationary supply member, a pair of movable members, one below and one above the supply member, means for moving said movable members across the ends of the supply member to position the movable members, and mechanism for releasing type from the member above the supply member to allow it to pass into the supply member, and mechanism for releasing type from the lower end of the supply member to allow it to pass into the movable member beneath it.

31. The combination of a stationary supply drum, adapted to hold longitudinal rows of type, a holding and releasing device at the bottom of each row, a member adapted to carry a type holder below the supply drum and movable toward the supply drum to release the type in the alined channel thereof.

32. The combination of a stationary supply drum having type channels, a shaft journaled axially in said drum, an arm on said shaft above the drum adapted to carry a type holder and having type holding and releasing means mounted on it, means for rotating said shaft, and mechanism for moving said shaft longitudinally to release the type from said arm.

33. The combination of a stationary supply drum having type channels, a shaft journaled axially in said drum, an arm on said shaft below said supply drum, type retain-

- ing means near the lower ends of the channels in the supply drum, means on the arm for operating the type retaining means, and mechanism for moving said shaft longitudinally to release the type. 5
34. The combination of a stationary supply drum having vertical type channels on its surface, a shaft journaled axially in said drum, an arm on said shaft above the drum adapted to carry a removable type holder, an arm on said shaft below said supply drum adapted to carry a removable type holder, type retaining means for the upper holder and for the lower ends of the channels in the supply drum, and mechanism for raising or lowering said shaft to operate such type retaining means, and means for rotating said shaft to position the arms with reference to the drum channels. 10
35. The combination of a stationary supply drum having type channels, a shaft journaled axially in said drum, an arm on said shaft above the drum adapted to carry a type holder and having type holding and releasing means mounted on it, an arm on said shaft below said supply drum adapted to carry a type holder, type retaining means near the lower ends of the channels in the supply drum, means on the arm below the drum for operating the type retaining means, and mechanism for raising or lowering said shaft to release the type from the upper arm or to the lower arm, and means for rotating said shaft to position the arms with reference to the drum channels. 20
36. The combination of a stationary supply drum having vertical type channels on its surface, a main shaft journaled axially in said drum, an arm on said shaft above the drum having type holding and releasing means mounted on it, an arm on said shaft below said supply drum, type retaining means near the lower ends of the channels in the supply drum, means on the arm below the drum for operating the type retaining means, mechanism for raising or lowering said shaft to release the type from the upper arm or to the lower arm, means for rotating said shaft to position the arms with reference to the drum channels, a pointer and dial to indicate such position, a driving shaft on which one member of the pointer and dial combination is mounted, means for rotating said last mentioned shaft, a bevel gear on said last mentioned shaft, a bevel gear on the main shaft meshing with the bevel gear already mentioned and connected with the main shaft to rotate with it but allowing the shaft to slide through it, and springs and movable collars on said main shaft tending to center the same while allowing it to be raised or lowered. 45
37. In a typesetting machine, the combination of an upright storage drum adapted to carry columns of type in its periphery; 55
- means adapted to engage the feet of the type to positively shove downwardly type in said drum, and mechanism for causing such downward shoving. 60
38. The combination of an upright storage drum adapted to carry columns of type in its periphery, means adapted to engage the feet of the type for shoving downwardly on type in the drum, a receiving channel for the type adapted to cooperate with the drum, means for rotating one of such cooperating parts to bring it into varied relation with the other, and means for locking such rotated part in desired position. 70
39. The combination of a drum having about its periphery a plurality of upright typeholding channels made by rails with overhanging edges mounted side by side parallel with the axis of the drum, whereby said channels are adapted to loosely confine type grooved on its opposite sides, two type-holders adapted to loosely confine type grooved on their opposite sides, one of such holders being above the drum and the other below it, hand-controlled means at the upper end of the drum for distributing type from the upper holder into the drum, and hand-controlled means at the lower end of the drum for assembling type from the drum into the lower holder. 80
40. The combination, with a type magazine having a plurality of open ended type channels, type extractors individual to the respective channels and each formed to act against a beveled portion of the type and thereby shove it longitudinally, a type holder movable transversely of said channels and into which said type are transferred from the open ends of said channels by said extractors, and means to operate said type extractors. 90
41. The combination of a type case having a plurality of type holding channels with open upper ends, a movable member adapted to travel over such ends and carry a column of type in alignment with any of said channels, a rotatable shaft for so moving said member, a transverse shaft geared with the shaft first mentioned and a handle or knob for turning the transverse shaft. 100
42. The combination of a type supply drum, a shaft journaled axially thereof, an arm on said shaft opposite the end of the drum, a type holder carried by said arm, mechanism for turning said shaft on its axis, mechanism for releasing type one at a time to or from said holder, a finger key located independently of such axial turning, and lever mechanism operated thereby to actuate the releasing mechanism independently of the position of the arm. 110
43. The combination of a stationary type supply drum, distributing mechanism, rotatable mechanism for positioning the distributing mechanism, and stationarily carried 120
- 125
- 130
- 135

finger actuated mechanism for directly operating the distributing mechanism.

44. The combination of a stationary supply drum, a member journaled therein and adapted to be turned on its axis, distributing and assembling mechanism positioned by such turning, finger keys, and means operated thereby to actuate the assemblage or distribution.

45. The combination of a stationary supply drum, mechanism for distributing type into the upper end thereof, mechanism journaled axially of the drum for positioning the distributing mechanism, mechanism shiftable axially of the drum for operating the distributing mechanism, and a finger key located independently of the distributing mechanism and adapted to actuate said shiftable mechanism.

46. The combination of a stationary supply drum having a plurality of type holding channels, a series of individual means for releasing the type from the respective channels, means to receive the released type, axially journaled means carrying such receiving means, and axially shiftable means to operate the release of the type.

47. The combination of a stationary storage member in the form of an upright drum, a type holder, rotatable means journaled axially of the drum adapted to carry said holder around in proximity to the end of the drum, and stationarily located finger operated means acting longitudinally of the drum to release the type.

48. The combination of a stationary storage member in the form of an upright drum, a type holder, rotatable means journaled axially of the drum adapted to carry said holder around in proximity to the end of the drum, a rotatable shaft geared with said journaled member, a knob or handle on said shaft, and finger keys for releasing the type.

49. The combination of a stationary storage member in the form of an upright drum, a type holder, rotatable means journaled axially of the drum adapted to carry said holder around in proximity to the end of the drum, a rotatable shaft geared with said journaled member, a knob or handle on said shaft, and a pointer and dial, one member of which is stationary and the other of which turns with said shaft.

50. The combination of a stationary storage member in the form of an upright drum, a type holder, rotatable means journaled axially of the drum adapted to carry said holder around in proximity to the end of the drum, a rotatable shaft geared with said journaled member, a knob or handle on said shaft, means shiftable axially of the drum to release the type, and a pair of finger keys adapted to operate said means.

51. The combination, with a member having a plurality of parallel straight rails

adapted to hold successive rows of grooved individual type arranged cylindrically about an axis, a split tube forming a holder and guide for a single row of such type, and means adjacent to one end of said member for guiding into proper presentation thereto the exit end of said split tube.

52. The combination, with a member having a plurality of parallel straight rails arranged cylindrically about an axis, said rails having overhanging edges adapted to hold successive rows of grooved individual type, a separatable holder for a single row of such type comprising a comparatively long tube having a slot the width of which is substantially equal to the distance between the edges of adjacent rails, whereby the portions of the tube on opposite sides of the slot are adapted to enter the grooves of the type and aline with the overhanging portions of the adjacent rails, and means adjacent to one end of said member for receiving and presenting in alinement therewith the exit end of the said holder.

53. The combination of a supply drum having on its periphery a plurality of adjacent overhanging rails providing type-holding channels between them, a shaft at the axis of said drum, a type holder, said holder and drum coöperating and said shaft being connected with one of them, means for rotating said shaft, and a stationarily located finger key for feeding the type between the holder and drum.

54. The combination of an upright storage drum having a plurality of type holding channels about its periphery, hand operated mechanism at the upper end of the drum for distributing type into the drum, hand operated mechanism at the lower end of the drum for assembling type from it, and hand operated means for changing at will the presentation of the drum and the coöperating type holder from which or into which the type is fed by said distributing or assembling mechanism.

55. The combination of a type magazine comprising a plurality of type channels side by side adapted to loosely confine type grooved on its opposite sides and allow it to gravitate toward the bottom of the magazine, a type holder above the magazine, a type holder below the magazine, mechanism for simultaneously changing the mutual presentation of the magazine and both type-holders, and means for discharging type from the upper typeholder into the magazine and from the magazine into the lower typeholder.

56. The combination of an upright drum having arranged longitudinally on its periphery a series of parallel holders for individual type, a column type holder above the drum near its periphery and a type holder below the drum near its periphery,

- mechanism for distributing type from the upper type holder into the drum, mechanism for assembling type from the drum into the lower type holder, hand actuated means 5 for operating said mechanisms, a shaft located at the axis of the drum, and means whereby the rotation of said shaft changes the mutual presentation of the type holders and drum.
- 10 57. The combination of an upright drum having arranged longitudinally on its periphery a series of parallel holders for individual type, a column type holder above the drum near its periphery and a type 15 holder below the drum near its periphery, mechanism for distributing type from the upper type holder into the drum, mechanism for assembling type from the drum into the lower type holder, hand actuated means 20 for operating said mechanisms, a shaft located at the axis of the drum, means whereby the rotation of said shaft changes the mutual presentation of the type holders and drum, a device adapted to be grasped by 25 the hand for rotating said shaft, and an indicator comprising a chart and pointer, one of which is moved according to the movement of said shaft, whereby the particular channel with which the holders may coöperate is indicated.

58. The combination, with a series of rails with overhanging edges and means for holding them equidistantly about an axis to provide a drum-like holder for a plurality of 35 parallel rows of type grooved on its opposite sides, of a separate single-row holder, consisting of a split tube adapted to engage with the grooves of the type and aline them with the adjacent end of the drum-like 40 holder.

59. The combination, with a series of rails and means for holding them equidistantly about an upright axis to provide a drum-like holder for a plurality of parallel rows 45 of type which drop by gravity, of a separate single-row holder, an intermediate member adapted to engage the single-row holder near that end which is adjacent to the drum-like holder and cause it to aline 50 longitudinally with one of the holders of the drum-like holder, a hand device for changing the presentation of the drum-like holder and single row holder, and finger operated mechanism independent of the hand 55 device for feeding type without change of alinement from one of said holders to the other.

60. The combination of an upright type case having a plurality of type holders open 60 at each end, mechanism for distributing type into the upper end of said holders, mechanism for assembling type from the lower end of said holders, a common finger key for actuating all of the assembling

movements, a second common finger key for actuating the distributing movements, the assemblage mechanism operating to prevent the type falling out of the case and the distributing mechanism to prevent the type falling into the case.

61. The combination, with a set of parallel rails held to constitute a drum-like receiver of parallel channels for rows of grooved type, of a removable holder for a single row of type, and a projecting pin 75 movable with the holder and offset laterally therefrom a distance corresponding to the distance between channels and adapted to enter the next adjacent channel for insuring registration of the exit end of said holder 80 with the channel desired.

62. The combination, with a plurality of straight rails with edges overhanging in both directions, means for holding them parallel with each other and arranged cylindrically about an axis whereby they may hold between them lines of individual type grooved on their opposite sides, and thus constitute a multi-channeled holder, a line holder in the form of a split tube adapted 90 to hold a single row of such grooved type, means for moving one of such holders about said axis, and a seat for the split tube holder adapted to hold it with its edges adjacent to the split alining with the overhanging 95 edges of adjacent rails of the multi-channeled holder.

63. The combination, with a type magazine having a plurality of type channels each adapted to contain a line of loose type located therein, of a combined type gate and extractor individual to each of said channels and normally sustaining the type therein against gravity by projecting into the space between successive type enabled by 100 bevels thereon, and mechanism to operate the gates and extractors of the various channels.

64. The combination, with a series of rails having overhanging heads and means for holding them equidistantly about an axis to provide a drum like holder for a plurality of rows of type, of a separate holder for a row of type, and a movable member having a seat adapted to be engaged by said 110 separate holder near that end which is adjacent to the drum-like holder, whereby both holders may be longitudinally alined, means for moving said movable member to present its holder to any row of the drum-like 115 holder, said separate holder comprising a tube having a slot parallel with its axis which slot is of substantially the same width as the distance between the heads of adjacent rails.

65. The combination of an upright type-holding member, means for feeding type into the upper end of it and out of the lower

end of it, and a rock shaft for controlling both of such feeds according to the direction of rocking.

66. The combination of a stationary typeholding member having a series of parallel typeholders arranged in an arc and a carrier pivoted on the axis of said arc and adapted to swing about the end of the typeholding member, means for swinging the carrier and moving it transversely toward the typeholding member, and means on the carrier for removably holding the temporary typeholder in alignment with any of said stationary typeholders.

67. The combination, with a type magazine having a plurality of type channels each adapted to contain a line of loose type located therein for gravitating movement, of a type holding and ejecting means individual to each of said channels and adapted to enter the interstices between the lowermost type of each channel and the next adjacent type, and mechanism to operate said means.

68. The combination, with a type magazine having a plurality of open end type channels, a type holder movable transversely of the ends of said channels, means to transfer said type from said holder to said channels also movable transversely thereof, and a shaft carrying said type holder and transferring means, and means operated by said shaft to operate said type transferring means.

69. The combination, with a type magazine having a plurality of type channels adapted to contain each a line of loose type, a type holder movable transversely of said channels, a shaft by which said type holder is supported, and mechanism operated by said shaft to transfer the type from said holder to said magazine.

70. The combination, with a type magazine having a plurality of type channels adapted to contain each a line of loose type, a type holder movable transversely of said channels, a shaft on which said type holder is mounted, mechanism operated by said shaft to transfer the type from said holder to said magazine, and finger mechanism to operate said shaft.

71. The combination, with a series of rails and means for holding them equidistantly about an axis to provide a drum-like holder for a plurality of parallel rows of type, of a separate single-row holder, and an intermediate member adapted to engage the single-row holder near that end which is adjacent to the drum-like holder and provide a

guiding channel alining with both holders.

72. The combination, with a series of rails and means for holding them equidistantly about an axis to provide a drum-like holder for a plurality of parallel rows of type, of a separate single-row holder, and an inter-

mediate member adapted to engage the single-row holder near that end which is adjacent to the drum-like holder and provide a guiding channel alining with both holders, and finger operated mechanism for feeding type from one of said holders to the other.

73. The combination, with a series of rails and means for holding them equidistantly about an axis to provide a drum-like holder for a plurality of parallel rows of type, of a separate single-row holder, and an intermediate member adapted to engage the single-row holder near that end which is adjacent to the drum-like holder and provide a guiding channel alining with both holders, and mechanism operated by movement of said intermediate member with its single-row holder toward the drum-like member for causing transfer of type between them.

74. The combination of a series of typeholders down which type may slide by gravity, a typeholder mounted below such series and adapted to move and have its upper end in proximity with the lower end of any one of such holders, and means for moving such last mentioned holder transversely of its first movement, and mechanism whereby such movement operates to transfer the type from one of the series of type holders into the movable holder.

75. The combination of a stationary storage member having a series of parallel type holding channels down which type may slide by gravity, mechanism movable crosswise of the end of such member and adapted to receive type ejected therefrom, mechanism for moving the last-mentioned mechanism transversely of its said crosswise movement, and a discharge controller for the type actuated by such transverse movement.

76. The combination, with a supply member having channels down which type may pass by gravity, of hand actuated means for distributing type into the upper end of it, hand actuated means for assembling type from the lower end thereof, and a tubular type holder having a slot parallel with its axis, said slot being of a width substantially equal to the width of any of said channels.

77. The combination of a series of typeholders arranged in a bank down which type may pass by gravity, an individual typeholder movable crosswise of the lower end of such bank, and means for moving such individual typeholder toward the holder of the bank to which it stands opposite and simultaneously releasing type from the bank to pass into such individual typeholder.

78. The combination of a type storage member having a plurality of parallel typeholders, an individual typeholder adapted to aline with any of the typeholders first mentioned, means for giving such individual typeholder a movement across the end of

- the storage member to select the desired one of such plurality of typeholders, and means for moving such individual typeholder toward the selected typeholder to which it is 5 opposite and by such movement releasing the type from the selected typeholder into the individual typeholder.
79. The combination of a series of upright typeholders arranged in a bank, an individual typeholder movable crosswise of the lower end of such bank, and means for moving such individual typeholder toward the holder of the bank opposite to which it stands and simultaneously releasing type from the bank to pass into such individual typeholder.
80. The combination of a series of parallel typeholders, a holder for a single column of type, means for giving said holder two movements, one to position it with reference to the holders, and the other to move it to release the type from the selected holder of the series.
81. The combination of a series of vertical typeholders, an individual typeholder mounted below such series and adapted to move and have its upper end in proximity with any one of such holders, and means for moving such individual holder transversely of its first movement, and mechanism whereby such movement operates to transfer the type from one of the stationary holders into the movable holder.
82. A stationary type storage member comprising a plurality of upwardly extending typeholders, a holder for a single column of type mounted below said storage member, and movable crosswise thereof to select a desired holder in the storage member, and means for moving the column typeholder toward the selected holder in the storage member, and mechanism whereby such movement releases type from the storage member and allows it to pass into the column holder.
83. In a typesetting machine, the combination of a stationary storage member having typeholders adapted to carry individual columns of type descending by gravity, one type above the other, means for preventing the type dropping out of their holders, an individual column typeholder, means for moving it transversely of the holders of the storage member to position it, means for thereafter giving it a movement to bring its upper end closer to the selected typeholder of the storage member, and means whereby such movement acts on the means which prevent the escape of the type from the storage member, and allow the bottom type to drop into the individual holder.
84. In a typesetting machine, the combination of a type storage member having a plurality of typeholders and an individual typeholder movable into proximity with any 65 of said plurality of holders, and a finger key for giving said individual typeholder another movement to bring it into effective cooperation with the selected typeholder of the plurality.
85. The combination of a series of typeholders arranged in a bank down which type may pass by gravity, said type holders having ribs adapted to occupy the grooves of type grooved on its opposite sides, an individual typeholder movable crosswise of the lower end of such bank and having two parallel edges adapted to occupy the grooves of such type, and means for moving such individual typeholder toward the holder of the bank to which it stands opposite and simultaneously releasing type from the bank to pass into such individual typeholder.
86. A stationary type case having parallel holders down which type may pass in columns, means at the bottom of each column for supporting such type, a receiving typeholder, means for guiding it in a path transverse to the lower ends of said parallel typeholders, and means for giving it another movement to cause it to receive the lowermost type.
87. A type case having a set of parallel rails with overhanging edges providing type channels between them down which type may pass by gravity in columns, means at the bottom of each column of type for supporting it, a receiving typeholder having a pair of separated edges adapted to align with the overhanging portions of adjacent rails, means for controlling the movement of such typeholder whereby it moves in a path transversely to the lower ends of said parallel typeholder, and means for giving said receiving typeholder another movement to cause it to receive the lowermost type in one of the columns.
88. A type case having parallel typeholders down which type may pass by gravity in columns, means at the bottom of each column for supporting such type, a receiving typeholder, means for controlling its movement whereby it may move in a path transversely to the lower ends of said parallel holders, a finger key, and mechanism controlled thereby for moving the receiving typeholder toward the lower end of the type case to receive the lowermost type in an adjacent channel.
89. The combination of a stationary type case having parallel typeholders composed of a series of up and down rails with edges overhanging in both directions whereby between each two rails is an undercut type channel, means at the bottom of each channel for supporting a column of type therein, a transversely movable typeholder having a pair of parallel separated edges adapted to receive and hold a row of type, a finger key, and mechanism actuated thereby for causing the receiving typeholder when properly po- 125

sitioned to move toward one of the parallel typeholders to enable it to receive the lower-most type.

90. A multi-channeled typeholder having 5 parallel rails with overhanging edges adapted to confine grooved type, a coöperating relatively movable typeholder having a type channel adapted to longitudinally aline with any of the channels of the typeholder, and a 10 projection movable therewith adapted to enter between rails at one side of those whose channel alines with said coöperating typeholder and insures accurate alinement of the respective channels.

91. The combination of a multi-channeled typeholder adapted to loosely confine grooved type, a coöperating relatively movable typeholder maintained in longitudinal alinement with said multi-channeled holder 20 and movable transversely to aline with any channel thereof, and a projection movable with such coöperating typeholder and adapted to enter a channel at one side of the channel with which the typeholder coacts.

92. The combination of a stationary typeholder having a series of parallel channels, a coöperating relatively movable typeholder having a type channel, a projection movable with such relatively movable holder, a finger key, and mechanism operated thereby to cause the projection to interlock with a channel to position the typeholder in longitudinal alinement with an adjacent channel.

93. The combination, with a stationary typeholder having a series of parallel channels down which type may pass by gravity, a transversely movable typeholder adapted to coöperate with various channels, projections movable transversely with such typeholder, and a finger key adapted to move the projection and the typeholder to lock the typeholder against displacement laterally, said movement of the typeholder operating to transfer the type.

94. The combination of a multi-channeled typeholder consisting of a vertical drum having about its periphery parallel overhanging rails, a coöperating relatively movable typeholder having a pair of separated edges adapted to aline with the overhanging portions of adjacent rails, means for moving such coöperating typeholder in an arc about the end of the drum, means for moving it toward the drum, and a projection 55 movable with it and adapted to enter between adjacent rails on such movement.

95. The combination of a magazine having a plurality of type channels adapted to contain each a line of type having beveled feet, 60 a type holder movable transversely of said channels, a releasing device for the type adapted to act on their beveled feet, and mechanism for operating said device to transfer the type from said magazine to said holder.

96. The combination, with a magazine provided with a plurality of type channels, of a typeholder mounted on the machine and coöperating with the magazine, means for revolving one of such parts with reference 70 to the other, means for locking the revolved part, and means for distributing the type singly from one of such parts to the other, said means engaging the foot of the type and forcing it positively in the direction of the 75 length of the column of type.

97. The combination of a stationary type case having parallel gravitation channels side by side with open ends, a distributing stick movable transversely to the upper end 80 of the type case, an assemblage stick movable transversely to the lower end of the type case, means at the lower end of each channel of the type case for supporting the columns therein, means at the lower end of the distributing stick for supporting the column in it, a pair of finger devices, and mechanism controlled thereby for ejecting the bottom-most type of the distributing stick into the type case and for ejecting the bottommost 85 type in the type case into the assemblage stick.

98. The combination, with a type magazine having a plurality of type channels adapted to contain each a line of loose type 95 with beveled feet, a type holder movable transversely of said channels, a series of releasing devices adapted to operate on the bevels of the type, and common operating means for the various releasing devices. 100

99. The combination of a magazine in the form of an upright drum adapted to carry columns of type in its periphery, a series of ejectors for the type, each adapted to engage the type in its respective column and move 105 with such type to shove it lengthwise of the column, common means for operating the various ejectors, and means for changing the relation of the drum to said common means by rotating one of them.

100. The combination, with an upright type case composed of a series of parallel rails with edges overhanging in both directions whereby each rail forms the wall of two adjacent channels, of a coöperating single-row typeholder comprising a tube having a slot parallel with its axis, the edges of the tube on opposite sides of the slot being adapted to aline with the overhanging portions of adjacent rails, means for supporting 115 an upright column of type in the tube, and means for releasing the bottommost type. 120

101. The combination, with a type case composed of a series of parallel rails with edges overhanging in both directions whereby each rail forms the wall of two adjacent channels, of a coöperating single-row typeholder comprising a tube having a slot parallel with its axis, the edges of the tube on opposite sides of the slot being adapted to 125 130

aline with the overhanging portions of adjacent rails, and a projection carried by such tube and adapted to enter a channel alongside of the one with which the tube alines.

5 102. In a typesetting machine, the combination of a storage drum having a plurality of type channels arranged in its periphery, a revolute shaft at the axis of said drum, a transverse shaft, gearing between the same 10 and the revolute shaft, a hand wheel on the forward end of the transverse shaft, a common type channel, said common type channel and drum being adapted to have their mutual presentation changed by means of 15 one of them being mounted on said revolute shaft and the other being stationarily carried.

103. The combination of an upright drum having a plurality of typeholding channels in its periphery, a typeholder above the drum and a typeholder below the drum, hand-controlled means for discharging type from the upper typeholder into the drum and hand-controlled means for discharging 25 type from the drum into the lower typeholder, and mechanism for simultaneously changing the mutual presentation of the drum and both typeholders.

104. The combination of an upright storage drum having typeholding channels in its periphery, a shaft at the axis of said drum, means for turning one of said members with reference to the other upon said axis, a typeholder above the drum, a typeholder below the drum, distributing mechanism controlling the transfer of type from the upper typeholder to the drum, assemblage mechanism controlling the transfer of type from

the drum to the lower typeholder, and finger key mechanism adapted to actuate the assemblage and distribution mechanism. 40

105. The combination of a supply member having a series of parallel type channels adapted to hold type having beveled feet, a series of releasing devices for the type in the 45 channels adapted to operate on their beveled feet, traveling means adapted to operate any of said devices, and a shaft supporting the traveling means.

106. A supply member having a series of 50 parallel type channels arranged so that type may slide down them by gravity, of a distributing device movable across the upper end of the type channels, an assemblage device movable across the lower ends of the 55 type channels, and assemblage and distribution mechanism acting on the feet of the type.

107. A supply member having a series of 60 parallel type channels arranged so that type may slide down them by gravity, of a distributing device movable across the upper end of the type channels, an assemblage device movable across the lower ends of the 65 type channels, and assemblage and distribution mechanism acting on the feet of the type, the distribution mechanism, traveling with the distributing device and the assemblage mechanism having a series of releasing 70 devices for the various channels.

In testimony whereof, I hereunto affix my signature in the presence of two witnesses.

HARRY C. GAMMETER.
